(57) **CLAIM**

The ornamental design for the shoe sole, as shown and described.

DESCRIPTION

FIG. 1 is a first perspective view of the shoe sole showing our new design;

FIG. 2 is a second perspective view thereof;

FIG. 3 is a third perspective view thereof;

FIG. 4 is a side view thereof;

FIG. 5 is a top view thereof; and,

FIG. 6 is a magnified side view thereof of area 6 circumscribed within FIG. 4.

The dash-dot-dash broken lines immediately adjacent the shaded areas represent the bounds of the claimed design while all other broken lines are directed to environment. The broken lines form no part of the claimed design.
